UNITED STATES PATENT OFFICE

166,782

TOILET TISSUE DISPENSER

Henry Weskrna, Belleville, N. J.

Application May 4, 1949, Serial No. 2,438

Term of patent 3½ years

(Cl. D4—3)

To all whom it may concern:

Be it known that I, Henry Weskrna, citizen of the United States of America, residing at Belleville, in the county of Essex and State of New Jersey, have invented a new, original, and ornamental Design for Toilet Tissue Dispenser, of which the following is a specification, reference being had to the accompanying drawing, forming a part thereof.

Fig. 1 is a perspective view of a toilet tissue dispenser showing my new design; and

Fig. 2 is a fragmentary rear perspective view of Fig. 1.

The dominant feature of my design resides in the surface ornamentation as shown.

I claim:

The ornamental design for a toilet tissue dispenser, substantially as shown and described.

HENRY WESKRNA.
